THE NATIONAL LITHOGRAPHING COMPANY
WASHINGTON, D. C.

UNITED STATES PATENT OFFICE.

JULIUS W. FLOWERS, OF NEWPORT, OREGON.

VICE.

SPECIFICATION forming part of Letters Patent No. 515,545, dated February 27, 1894.

Application filed October 13, 1893. Serial No. 488,033. (No model.)

To all whom it may concern:

Be it known that I, JULIUS W. FLOWERS, a citizen of the United States, and a resident of Newport, in the county of Lincoln and 5 State of Oregon, have invented certain new and useful Improvements in Vises; and I do hereby declare the following to be a full, clear, and exact description of the invention, such as will enable others skilled in the art to which it applies 10 to make and use the same.

This invention relates to an adjustable vise, and has for its object to provide simple and effective means for regulating the device to various sizes and adapting the same for 15 different uses by means of quickly operating mechanism which can be easily and readily handled.

With these and other objects in view, the invention consists of the construction and arrangement of the several parts which will be 20 more fully hereinafter described and claimed.

In the drawings: Figure 1 is a side elevation view of a vise embodying the invention and shown open. Fig. 2 is a longitudinal vertical section on line x. x. Fig. 3. Fig. 3 is a 25 top plan view.

Similar numerals of reference are employed to indicate corresponding parts of the several figures.

Referring to the drawings, the numeral 1 designates a stationary jaw which has its lower end securely fastened to the bench and is bifurcated as at 2 at the lower portion thereof and formed with a slot 3 at the upper part 30 thereof adjacent to the jaw or head 4 of the same. Through the lower bifurcated portion of the jaw 1 extends a lower bar 5 which is pivotally connected by a pin 6 through the said jaw 1 at the extreme lower portion thereof 35 to allow a slight play, and said bar is also formed with a series of openings 7 whereby it may be adjusted longitudinally in the said jaw 1 by removing the pin 6 to permit an adjustment of the parts of the vise in this direction. The upper part of the said bar 5 carries a tube 8 and adjacent to said tube is an upward extension 9 carrying two sets of hinge lugs 10 to the uppermost of which is pivotally connected the end of an operating 40 lever 11 and to the lowermost is pivotally attached a fulcrum bar 12 which is secured to 45 the lever 11 by a short link 13 in a pivotal manner.

Pivottally attached to the opposite end of the fulcrum bar 12 is a link 14 which is also secured in a pivotal manner to an operating block 15 having attached thereto the lower end of a second jaw 16. The second jaw 16 is free to move to and from the jaw 1 and is also formed with a lower bifurcation 17 and 50 an upper slot 18 adjacent to its head 19. The operating lever 11, together with the link 14 and the block 15 extends through the lower bifurcated portions of the jaws 1 and 16, and the said block 15 is movable over the bar 5 55 and is formed with a short tube 20 in which is secured one end of a coiled spring 21 whose opposite end is secured in the tube 8 and as shown in Fig. 2 when the jaws are released to separate the said tube 20 moves toward the 60 said tube 8 and it closes the coiled spring 21. The free end of the lever 11 is provided with a loop 22 by which it is operated and when said lever is depressed as shown in Fig. 2 the fulcrum bar 14 is arranged longitudinally parallel or in alignment with the fulcrum bar 12 to thereby force the lower end of the jaw 16 65 outwardly and bring the head thereof more closely to the head of the jaw 1. This mechanism serves as a primary adjustment for the 70 jaw 16 and to complete the securing action of the heads of the said jaws a positive secondary adjustment is employed which consists of a bar 23 which passes through the 75 slots in the upper portions of the jaws 1 and 16 and on one side is recessed or notched as at 24 for engagement with a catch lever 25 having a nose 26 adapted to take into said recess a fulcrum on the adjacent portion of the jaw 1. This catch lever is spring actuated and is provided with a handle as fully 80 shown whereby it may be disengaged from a holding position. A bar 23 adjacent to one end is slotted as at 27 and therein is mounted a clamping lever 28 which has a portion 85 thereof passing through the slot in the said bar and adapted to bear against the outer adjacent portion of the jaw 16 to clamp the head thereof against the head of the jaw 1. The 90 clamping lever set forth serves as a regulator to always hold the vise in readiness for use and the catch lever holds the bar 23 against 95 100

accidental disengagement and also serves to retain the requisite adjustment which is made when the lever 11 is in raised position as shown in Fig. 1 and when the said lever 11 is lowered a clamping action of the jaw heads is produced against the article to be held, by a quick and ready operation. By placing the lower spring in tubes, dust and chips are prevented from injuring the same or interfering with the proper action thereof.

It will be seen that the device can be adjusted to accommodate various widths by simple and efficient means and if after the primary adjustment is made through the lever 11 it is still desired to press the piece of wood or other article still tighter in the jaws of the vise, the clamping lever or regulator is operated to produce this additional pressure as it will be seen that the said regulator can at all times be employed to increase or decrease the pressure as may be desired. The opening or loop in the free end of the lever 11 is adapted to be engaged by the foot of the operator for convenience and facility in operating the said lever. Of course it will be understood that the jaws and other parts of the device may be made of any suitable material in accordance with the use desired and in making the adjustment of the several parts it will be understood that after the parts are regulated to a certain width they will remain in such adjustment until further changed thereby making it exceptionally convenient in holding a series of boards or other devices of a uniform thickness.

It will be obviously apparent that many minor changes in the construction and arrangement of the several parts might be made and substituted for those shown and de-

scribed without in the least departing from the nature or spirit of the invention.

Having thus described the invention, what is claimed as new is—

1. In a vise, the combination of a stationary jaw, a movable jaw, an adjusting bar extending through the upper portions of said jaws, a clamping lever or regulator attached to said bar and adapted to engage the outer upper portion of the movable jaw, and a block or shoe attached to the lower portion of the movable jaw, a spring connected to said block or shoe, an operating lever and a link between said operating lever and the block or shoe, substantially as described.

2. In a vise, the combination of a stationary jaw, a bar movable and adjustable attached to said stationary jaw, a carrying tube on said bar, an operating lever pivotally connected to the upper portion of said bar, a fulcrum lever also pivotally attached to the rear portion of said bar and connected to the lever by a link, a movable jaw adjacent to said stationary jaw, a block or shoe attached to said movable jaw and having a spring secured in a tubular portion thereof, the opposite end of said spring being connected with in the tube of the aforesaid bar, a link connecting the fulcrum bar with the shoe, and an upper secondary adjustment for the jaws, substantially as described.

In testimony whereof I have signed this specification in the presence of two subscribing witnesses.

JULIUS W. FLOWERS.
